[57] **CLAIM**

The ornamental design for a tread and shoulder portion of a vehicle tire, as shown and described.

DESCRIPTION

FIG. 1 is a front perspective view of a tread and shoulder portion of a vehicle tire showing my new design, it being understood that the tread and shoulder pattern repeats uniformly throughout the circumference of the tread and shoulder;

FIG. 2 is a front view of the tire of FIG. 1 it being understood that the back view is the same; and,

FIG. 3 is a side view of the tire of FIG. 1 shown at a reduced scale, it being understood that the other side is the same.
